UNITED STATES PATENT OFFICE

MELVILLE KEIM, OF CHICAGO, ILLINOIS, ASSIGNOR TO THE APEX PRODUCTS CORPORATION, OF CHICAGO, ILLINOIS, A CORPORATION OF ILLINOIS

DESIGN FOR A DISPLAY STAND

Application filed July 8, 1929. Serial No. 31,966. Term of patent 14 years.

To all whom it may concern:

Be it known that I, MELVILLE KEIM, a citizen of the United States, residing at Chicago, in the county of Cook and State of Illinois, have invented a new, original, and ornamental Design for Display Stands, of which the following is a specification, reference being had to the accompanying drawings, forming a part thereof, and in which,—

Fig. 1 is a front view of a display stand showing my new design,

Fig. 2 a side view of the same, and

Fig. 3 a top plan view of the same.

I claim:

The ornamental design for a display stand, as shown.

MELVILLE KEIM.
